US0D1022080S

(12) **United States Design Patent** (10) Patent No.: **US D1,022,080 S**
(45) Date of Patent: ** Apr. 9, 2024

(54) **ADJUSTABLE DUMBBELL**

(71) Applicant: **Guangdong Kangmo Health Technology Co., Ltd.**, Guangdong (CN)

(72) Inventor: **Liping Zhong**, Guangdong (CN)

(73) Assignee: **Guangdong Kangmo Health Technology Co., Ltd.**, Guangdong (CN)

(**) Term: **15 Years**

(21) Appl. No.: **29/905,694**

(22) Filed: **Oct. 24, 2023**

(51) LOC (14) Cl. **21-02**

(52) U.S. Cl.

USPC **D21/681**

(57) **CLAIM**

The ornamental design for an adjustable dumbbell, as shown and described.

DESCRIPTION

FIG. 1 is a front, right and top perspective view of an adjustable dumbbell, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an exploded view thereof; and,

FIG. 10 is an exploded view thereof.

The broken lines depict portions of the adjustable dumbbell that form no part of the claimed design.

1 Claim, 10 Drawing Sheets
